UNITED STATES PATENT OFFICE.

NELSON T. FULLER, OF NEW BEDFORD, MASSACHUSETTS.

BRICK-CLEANING MACHINE.

Application filed February 15, 1921. Serial No. 445,064.

To all whom it may concern:

Be it known that I, NELSON T. FULLER, a citizen of the United States, residing at New Bedford, in the county of Bristol and 5 State of Massachusetts, have invented new and useful Improvements in Brick-Cleaning Machines, of which the following is a specification.

This invention relates to certain new and 10 useful improvements in brick cleaning machines, and the primary object thereof is to provide a machine which embodies a mechanically operated cutting or cleaning means for removing the mortar from the 15 bricks.

A further object of the invention is to provide a rotating cutter for effecting removal of the mortar, and to provide a series of removable cutter blades which can be removed, 20 sharpened and replaced.

A still further object of the invention is to provide a cutter and a brick holding and feeding means which will enable the bricks to be gradually moved or advanced into the 25 effective cutting plane of the cutter to thereby remove the mortar.

Other and further objects will be later set forth and manifested in the course of the following description.

30 In the drawings:

Figure 1, is a front elevation of the invention:

Figure 2, is an end elevation:

Figure 3, is an enlarged detail view in 35 top plan and partly broken away of the cutting wheel:

Figure 4, is a rear side elevation of the cutting wheel;

Figure 5 is an enlarged section on line 40 5—5 of Figure 4, and

Figure 6, is a detail perspective view of one of the cutting blades.

In proceeding in accordance with the present invention, any suitable supporting frame 45 may be employed, for example a structure embodying a horizontal base 1 having supporting legs 2 and a table or work bed 3 held by standards 4.

A shaft 5 is journaled in bearings 6 and 50 has a loose pulley 7 and a fast pulley 8 thereon, with a belt 8' trained about the driving wheel of a suitable motor 9. A cutter wheel 10, preferably of cast form, is mounted on the front end of the shaft 5, 55 and is formed with a series of radial slots 11, inclined with respect to the plane of ro-

tation of the wheel as depicted in Figure 3 of the drawings. The bottoms of the inner ends of the slots are inclined downwardly and inwardly to form undercut parts in 60 which the approximately inner V-shaped ends or toes 12 of the cutter blades 13 are conformably engaged so as to be held against movement outwardly of the slots. In order to rigidly secure the blades in the 65 slots, the outer ends thereof have lugs 14 engaged by a ring 15 hinged at 16 and having its ends secured together by a suitable fastening device for instance the clamping screw 17 depicted in Figures 1 and 3 of the 70 drawings. The ring 15 is held fixed with relation to the wheel by means of angular or L-shaped clamping arms 18 equipped with screws 19 that bear against the rear face of the cutter wheel. Obviously as many of 75 these arms or dogs 18 may be employed as may be found necessary for the stated purpose.

The means for holding or guiding and feeding the bricks to the cutter embody a 80 bearing 20 attached to the table 3 and in which a rod 21 has sliding movement, the rod having a face plate 22 secured thereto to engage the bricks and move same into engagement with the cutter. An adjustable stop 23 is arranged on the table 85 adjacent to the face plate 22. The outer end of the rod 21 is equipped with spaced nuts or collars 24 between which a curved and slotted arm 25 operates, the 90 latter being pivoted at 26 to the table 3 and connected to a depending link 26'. The link in turn is connected to a foot treadle or lever 27 pivoted to a stirrup 28 supported by the bed or base 1. A spring 29 is 95 also connected to the treadle and to the table 3 so as to return the treadle to normal upon depression thereof. A hood or guard 30 surrounds the cutting wheel and is secured at its ends to the base 1.

In operation the motor is started and rotates the cutter clockwise or towards the stop 23, the brick being placed with one end or side engaged with the stop and a second side or end engaged with the plate 22, 105 whereupon the treadle is depressed by the foot of the operator to effect inward movement of the face plate and thereby of the brick toward the cutter, the latter removing the mortar according to the speed at which 110 the brick is fed thereto. In this way the mortar can be removed by a somewhat

grinding or slicing action on the mortar and in this manner all faces or ends of the bricks can be freed of the mortar.

It will be further seen that the cutter operates in a direction down on the brick and also in a direction towards the stop, consequently the brick requires no further holding, the face plate 22 also contributing in proper support of the brick during the cutting action. Upon release of the treadle the spring instantly moves the face plate away from the cutter so that the brick can be easily and quickly removed or turned to present another face to the cutter. The table 3 is arranged adjacent to the front end of the shaft 5 and extends diametrically of the cutter wheel so that the action of the cutting blades will be as just described.

What is claimed is:

- 20 1. In a brick cleaning machine, a cutter including a wheel having radial slots the inner ends of which are undercut, blades fitted in the slots and having their inner ends shaped to engage the said undercut end walls 25 of the slots, lugs on the outer ends of the blades, a split ring engaging over the lugs to hold the blades in the slots, and clamping arms on the ring to hold the latter to the wheel.
- 30 2. In a brick cleaning machine, a base, a shaft supported thereabove, means to drive the shaft, a cutter wheel on the front end of the shaft, a table supported by and above the base and extending diametrically across 35 the wheel, a stirrup carried by the base and depending therefrom, a foot treadle pivoted to the stirrup, feeding means for the bricks arranged on the table, and means actuated by the treadle to operate said feeding means.
- 40 3. In a brick cleaning machine, a cutter including a wheel having radial grooves in its front face and having undercut parts at the inner ends of the grooves, blades having their inner ends shaped to engage in the 45 undercut parts and having lugs on their outer ends the outer edges of which lugs lie substantially flush with the periphery of

the wheel, a ring seated on the periphery of the wheel and on said outer edges of the lugs and having an inwardly extending part engaged with the front sides of the lugs, inwardly extending parts on the ring extending over the back face of the wheel, set screws projected through the last named parts and impinged against the back of the wheel, means to rotate the wheel, and a support on which the bricks are placed and moved to engage the blades.

4. In a brick cleaning machine, a cutter including a wheel having radial grooves in its front face and having undercut parts at the inner ends of the grooves, blades having their inner ends shaped to engage in the undercut parts and having lugs on their outer ends, a ring seated on the periphery of the wheel and having an inwardly extending part engaged with the front sides of the lugs, means to secure the ring to the wheel and for causing the inwardly extending part thereof to draw the lugs against the bottoms of the grooves and for preventing movement of the blades longitudinally of the grooves, means to rotate the wheel and a support on which the bricks are placed and moved to engage the blades.

5. In a brick cleaning machine, a wheel having radial grooves which are undercut at their inner ends, blades fitted in the grooves and having shoulders at their outer ends, a member engaged over the periphery of the wheel and having a front part engaging the shoulders to hold the blades against all movement in the grooves, means to secure the member to the wheel, means to rotate the wheel, and a support on which the bricks are placed and moved to engage the blades.

In testimony whereof I have hereunto set my hand in presence of two subscribing witnesses.

NELSON T. FULLER.

Witnesses:

HENRY W. MASON,
ROBERT A. TERRY.
